UNITED STATES PATENT OFFICE.

WILLIAM H. BATES, OF DETROIT, MICHIGAN.

CLAMP FOR ATTACHING SPRINGS TO CORRUGATED CROSS-BARS.

No. 926,381.

Specification of Letters Patent.

Patented June 29, 1909.

Application filed April 18, 1906, Serial No. 312,298. Renewed March 15, 1909. Serial No. 483,584.

To all whom it may concern:

Be it known that I, WILLIAM H. BATES, a citizen of the United States, residing at Detroit, in the county of Wayne, State of Michigan, have invented certain new and useful Improvements in Clamps for Attaching a Spring to a Corrugated Cross-Bar; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a clamp for attaching a spring to a corrugated cross bar, especially designed for use in connection with the manufacture of upholstered seats and similar articles, and consists in the construction and arrangement of parts herein-after fully set forth and claimed.

The object of the invention is to provide simple and efficient means for attaching the cushion springs to the cross bar of a seat frame in a manner to enable said springs to be quickly and firmly secured in place and readily adjusted to any desired location on the supporting bar, the arrangement being such as to provide for automatically locking the springs in position, and for allowing of the ready removal of the springs when desired.

The above object is attained by the structure illustrated in the accompanying drawing, in which:—

Figure 1 is a fragmentary plan view of a portion of a seat frame, showing a corrugated cross bar thereof, and two springs secured thereto by my improved clamping means. Fig. 2 is a side elevation of Fig. 1. Fig. 3 is a fragmentary view in perspective, showing the clamp formed integral with the lower end of the spring. Fig. 4 is a fragmentary view in horizontal section, as on line 4—4 of Fig. 2.

Referring to the characters of reference, 1 designates one of the corrugated bars, of which there may be employed any number desired, and which cross between the rails 2 of the seat frame, the ends of said bars being secured to said rails in any suitable manner. The bars are formed of strips of iron, of suitable gage, and are mounted edgewise so as to present said corrugations laterally.

The springs 3 are of the usual spiral formation, and formed integral with the lower coil 4 thereof is a rectangular clamp which stands nearly at right-angles to said coil in line with the axis of the spring, and consists of the opposed vertical sides 5 and 6, the bottom horizontal portion or cross piece 7 connecting said sides at their lower ends, and the upper horizontal cross piece 8 forming in effect a rectangular frame, there being a downwardly extending tongue 9 from the upper cross piece 8 which depends within said frame in the plane of the sides 5 and 6. In placing the spring upon the corrugated bar, the tongue 9 is sprung laterally sufficiently to allow the bar 2 to pass between it and the sides 5 and 6 of the rectangular clamp. The clamp is then forced downwardly over the bar with the tongue 9 lying in a depression of the corrugation on one side thereof, and the sides 5 and 6 lying in depressions on the opposite side of said bar. The depth of the rectangular frame of the clamp is such as to cause the lower cross piece 7 thereof to engage under the lower edge of the corrugated bar when the clamp is forced into position thereon, thereby firmly locking the clamp to the bar and preventing its withdrawal until it is sprung sufficiently to carry the lower cross piece 7 from under the lower edge of the bar 1 when said clamp may be removed by drawing upwardly on the spring.

The clamp being formed integral with the spring, its parts are sufficiently resilient to cause the lower cross piece 7 to spring into engagement under the edge of the corrugation of the bar in the hollow of which the tongue 9 lies when the clamp is forced into place, serving as an automatic lock for securing the clamp in position.

By forming the clamp integral with the lower coil of the spring, no additional parts are required to secure the spring upon the bar, enabling the spring to be quickly mounted. The spaces between the corrugations of the bar are equal to the distance between the sides 5 and 6 of the clamp, thereby enabling the spring to be secured to the bar at any desired point thereon and moved from place to place along the bar at will. Because of the corrugations in the supporting bar, the clamp cannot slide thereon, but instead is firmly held against movement along the bar when it is once placed in position.

Having thus fully set forth my invention,

what I claim as new and desire to secure by Letters Patent is:—

1. In a device for the purpose set forth, the combination with a cross bar having a lateral bend, of a spring and a clamp formed upon the spring and engaging the opposite sides of said bar with tension to clamp the spring thereto, a part of said clamp engaging under the lateral bend of the cross bar.
- 10 2. In a device for the purpose set forth, the combination of a corrugated cross bar positioned to dispose the width of the bar vertically, a spring and a clasp formed upon the base of the spring shaped to engage in the corrugations on opposite sides of said bar to clamp the spring thereto and to engage the under edge of one of said corrugations.
- 15 3. In a device for the purpose set forth, the combination of a bar having corrugations therein, said bar being disposed to present the width thereof vertically, a spring having a clamp formed thereon, said clamp consisting of members which embrace the opposite vertical sides of the bar and lie in corruga-
- 20 tions thereof, and having a cross piece which engages under the lower edge of one of the corrugations of said bar.
- 25

4. In a device for the purpose set forth, the combination with a supporting bar, of a spiral spring having a clamp formed integral 30 with the base thereof, said clamp consisting of vertically disposed spring members to engage the opposite sides of said bar, and a horizontal cross piece to engage a portion of the lower edge thereof.

35 5. In a device for the purpose set forth, the combination of a cross bar, having corrugations therein, a spiral spring, a clamp formed integral with the base of said spring, said clamp consisting of a rectangular frame having vertical sides which engage in the depressions of the corrugations on one side of the bar, a spring tongue which engages in a depression on the opposite side of the bar and a cross piece which engages the lower edge of 40 the corrugation in the hollow of which the spring tongue lies.

45 In testimony whereof, I sign this specification in the presence of two witnesses.

WILLIAM H. BATES.
